ELECTRIC SWITCH

George J. Meuer, Milwaukee, Wis., assignor to
Cutler-Hammer, Inc., Milwaukee, Wis., a corpora-
tion of Delaware

Application April 26, 1937, Serial No. 138,912

9 Claims. (Cl. 201—48)

This invention relates to improvements in electric switches. The invention relates more particularly to snap switches adapted for use in conjunction with radio rheostats and the like.

5 An object of the invention is to improve and simplify the details of construction, arrangement and operation of switches of the aforementioned character.

Another object is to provide for reduction in 10 over-all dimensions of such a switch of given current controlling capacity.

Another object is to provide a novel form and arrangement of the stationary and movable contact elements of the switch.

15 Another object is to minimize the number of different parts required for production of switches having various different control characteristics.

Another object is to provide a novel form of switch base and a novel form of mounting means 20 therefor.

Another object is to provide a novel form of insulating carrier adapted to alternatively accommodate one or more bridging contactors for the switch, according to the circuit controlling arrangement desired.

Another object is to provide a substantially dust-tight switch of the character aforementioned.

Other objects and advantages of the invention 30 will hereinafter appear.

The accompanying drawings illustrate various embodiments of the invention which will now be described; it being understood that the embodiments illustrated are susceptible of modification 35 in respect of certain details of construction thereof without departing from the scope of the appended claims.

In the drawings,

Figure 1 is a top plan view (double-scale) of a 40 single pole single throw snap switch constructed in accordance with my invention.

Fig. 2 is a sectional view, on the line 2—2 of Fig. 1, but showing the same mounted in a metal casing in conjunction with a radio rheostat.

Fig. 3 is a bottom plan view of the combination of elements illustrated in Fig. 2.

Fig. 4 is a top plan view of the switch base shown in Fig. 1 prior to attachment of the switch 50 parts thereto.

Fig. 5 is a sectional view, on the broken line 5—5 of Fig. 1.

Fig. 6 is an enlarged fragmentary sectional view, with parts in elevation, illustrating the contactor in bridging relation to the stationary con-

tacts of the switch, and showing the manner of rigidly attaching the lower contact to the base.

Fig. 7 is a view similar to Fig. 1, but showing added parts to provide a switch of the double pole single throw type.

Fig. 8 is a sectional view, on the broken line 8—8 of Fig. 7.

Fig. 9 is a bottom plan view of a switch having a slightly modified form of base to accommodate a bus member for electrically connecting two of 10 the stationary contacts of the switch.

Fig. 10 is a sectional view, on the broken line 10—10 of Fig. 9, showing the arrangement of a pair of bridging contactors to provide a three-way switch.

Fig. 11 is a fragmentary top plan view of a base having parts arranged to provide a switch of the so-called four-wire type, in which a common electrical connection is provided for the four wiring terminals in the "on" position of the switch. 20

Fig. 12 is a sectional view, on the broken line 12—12 of Fig. 11, illustrating the bus member providing an electrical connection between the bridging contactors of the switch.

Fig. 13 is a perspective view of a modified form 25 of combined contact and terminal member, which is stamped from a bimetallic punching.

Fig. 14 is a plan view of the flat, punched insulating plate or carrier.

Fig. 15 is an enlarged fragmentary sectional view, similar to Fig. 6, but showing a modified form of combined contact and terminal member and the manner of attaching the same to the base, and

Figs. 16 to 20 are views of a switch having a modified form of actuating member, and a modified form of supporting and operating means for the switch as a whole.

Referring first to Figs. 1 to 6, the numeral 25 designates the switch base, which is molded from 40 a suitable insulating material, such as the phenol formaldehyde condensation product sold commercially under the trade name of "Bakelite." Base 25, which is preferably of substantially circular contour is provided with a substantially 45 cylindrical recess 26 opening to the upper surface thereof. As best illustrated in Fig. 4, recess 26 is provided on its bottom wall with a projection or boss 27 forming a substantially triangular bearing ledge for the flat punched insulating plate 28 which serves as the contactor carrier of the switch. Superimposed upon plate 28 is a punched and stamped sheet metal actuator 29, the main body portion of which is of substantially diamond-shape. An opening 27a pen- 50

trates the projection 27 to accommodate the shank of a pivot post 30; and plate 28 and actuator 29 are respectively provided with openings 28^a and 29^a (Figs. 2 and 14) which register with each other to accommodate the enlarged portion 30^a of said post. Pivot post 30 is provided with a head 30^b to prevent upward displacement of parts 28 and 29, and the shank of post 30 is upset over the bottom surface of base 25, as shown at 30^c, to 10 secure said parts in assembled relation.

The peripheral wall of recess 26 is provided with a pair of ribs or inward projections 31 and 32 which are adapted for engagement alternately by the angularly arranged edges of the main 15 body portion of actuator 29, to limit the oscillatory movements of the latter. The provision of ribs 31 and 32 minimizes the required width or dimensions of the metal blank from which actuator 29 is formed. Actuator 29 is provided 20 as shown with a pair of sheared and upwardly struck arms 29^a, 29^b, arranged at a predetermined angle relatively to each other to provide for transient engagement thereof alternately by 25 an operating member of suitable form. Such an operating member is shown at 33 in Fig. 2, the same comprising a sheet metal member of substantially U-shape in horizontal cross section; member 33 being rigidly attached to shaft 34, in an eccentric relation, for rotation with the 30 latter.

As illustrated in Fig. 4, the bottom wall of recess 26 is provided with two sets of sub-recesses 35, 36, 37 and 38, 39, 40 which are preferably initially provided with relatively thin diaphragms integral with the side walls thereof. When a single pole double throw switch having normal operation (as shown in Fig. 1) is to be produced, the diaphragms of the set of recesses 38, 39, 40 are broached out or removed, the 40 diaphragms of the set of recesses 35, 36, 37 being permitted to remain intact. A one-piece combined contact and wiring terminal member 41 has the reduced upper end 41^a inserted upwardly through the opening provided by removal 45 of the diaphragm from sub-recess 40, and the projecting portions of said upper end 41^a, as shown at 41^b, 41^c in Fig. 6, are upset over the bottom wall of recess 26, as shown in full lines in this figure. As shown in Fig. 6, member 41 is 50 provided with shoulders engaging the lower surface of base 25, whereby the upper or contact edge 41^d of member 41 is positioned substantially flush with, or even slightly below, the bottom wall of recess 26. The depending lower end 41^e 55 of member 41 is provided with an opening to facilitate attachment of a terminal wire (not shown). Also as shown in Figs. 4 and 5, those portions of recesses 37 and 40 adjacent to the bottom wall of recess 26 are substantially wider 60 than the stationary contact portions to be positioned therein, to insure engagement of the respective contact heads 47^a with said contact portions, even after the latter are considerably worn, and to minimize deposition of metal particles upon the bottom wall of said recess. 65

A one-piece resilient sheet metal contact and wiring terminal member has a perforated portion 42 seated flatwise upon the bottom wall of recess 26, a headed rivet 43^a being preferably insertable downwardly through the perforation in said portion and through the opening provided by removal of the diaphragm from sub-recess 39, and having its shank 43^b upset over the lower surface of base 25 (see Fig. 3). Extending downwardly at a substantially right angle to portion 70

42, and penetrating the opening provided by removal of the diaphragm from sub-recess 39, is a portion 42^a which is perforated as shown in Fig. 2 to facilitate attachment of a terminal wire. A portion 42^b is bent upwardly at substantially a 5 right angle to portion 42^a; and a curved arm 42^c is bent to extend substantially horizontally in a plane a substantial distance below the upper surface of base 25. The free end of arm 42^c is bent to extend downwardly and then upwardly 10 (as best shown in Fig. 5) to provide a contact tip 42^d which overlies the aforementioned contact edge 41^d (Fig. 6) of member 41.

The aforementioned insulating plate 28 is provided with a relatively large opening 28^b intermediate the ends thereof, said opening being adapted to provide clearance for a coiled compression spring 43, one diametrically extending end portion 43^a of which is inserted upwardly through a bearing opening provided in the forward end portion 29^c of actuator 29, said end portion 29^c being preferably bent downwardly (Fig. 2) to lie within the plane of plate 28. Seated within the forward end of spring 43 is a metal cup member 44 which is adapted to bear 25 against an abutment 28^c formed at the forward end wall of opening 28^b.

Formed integrally with the bottom and peripheral walls of recess 26 are a pair of abutments 45 and 46, against the vertical surfaces of 30 which the plate 28 is respectively adapted to abut or strike to limit oscillatory movements of said plate. As best illustrated in Fig. 5, abutments 45 and 46 end in a plane substantially below the upper surface of base 25 to avoid interference between the same and the arms of the resilient contacts, one of which is shown at 42^c in this figure.

The forward end 28^d of plate 28 is preferably wider than the main body portion thereof, and 40 said end is provided with an arcuate series of four openings 28^e, 28^f, 28^g and 28^h, into any one of which the reduced or shank end 47 of a rivet form of contactor may be freely inserted upwardly, the substantially hemispherical head 45 portion 47^a of which contactor is positioned between plate 28 and the bottom wall of recess 26. For a single pole switch having normal operation, as shown in Fig. 1, the contactor 47 is positioned within the plate opening 28^e. Thus 50 with the parts as shown in Fig. 1, the switch is in the "off" position, whereas upon a predetermined degree of movement of actuator 29 in a counterclockwise direction, plate 28 will move with a snap action in a clockwise direction to 55 effect bridging engagement of contactor 47 with contact tip 42^d and contact edge portion 41^d.

As will be apparent from Fig. 1, the switch is "on" upon snap movement of plate 28 in a clockwise direction to one of its extreme positions, 60 and the switch is "off" upon snap movement of plate 28 in a counterclockwise direction to its other extreme position, the contactor being positioned within plate opening 28^e. The exact reverse of this function may be obtained by omitting the contactor 47 from opening 28^e and placing the same within plate opening 28^g. The reverse of the electrical function provided by the switch of Figs. 1 to 6 may likewise be provided by omitting the contactor 47 from plate opening 70 28^e and placing the same in opening 28^g, the member 41 in such an arrangement being omitted from the sub-recess 40 and placed in the opening to be provided upon removal of the diaphragm from sub-recess 37; the left-hand com- 75

- bined contact and wiring terminal member 42 of Fig. 1 being omitted, and a right-hand member like that shown at 48 in Fig. 7 being employed. With the stationary contact and terminal members positioned in the manner just described, an electrical function identical with that of the switch of Fig. 1 may of course be provided by employment of a single contactor 41 positioned within the plate opening 28^b.
- 10 The bottom wall of recess 26 is preferably provided with a relatively shallow sub-recess or indentation of the form best illustrated at 28^a in Figs. 1, 2 and 4. As best illustrated in Fig. 5 the shank end of rivet contactor 47 is preferably rounded to facilitate movement thereof into engagement with the flared or curved portion of contact tip 42^c. The stationary combined contact and terminal members and the contactor are preferably silver-plated to improve the appearance as well as the electrical characteristics thereof. Members 41 and 47 are preferably formed of copper, whereas resilient member 42 is preferably formed of an alloy, such as phosphor bronze or beryllium copper.
- 25 I prefer to mount or support the switch base 25 in the manner illustrated in Fig. 2. Thus I provide in the external surface of base 25 a pair of diametrically opposed curved channels or grooves 49 and 50 which are adapted to accommodate the curved arms or extensions 51 and 52 of an inverted cup-shaped metal casing designated in general by the numeral 53. Arm 52 is provided with a lug 54 which is bent inwardly to lie within a recess of corresponding shape provided in the lower surface of base 25 (Figs. 2 and 3); and arm 51 is provided with a pair of lugs 55 and 56 which are bent inwardly to lie within suitable recesses in said lower surface of base 25, in a relation to clear the upset end 39^c of pivot post 38.
- 40 The rheostat, of which parts are shown in Figs. 2 and 3, is not claimed herein per se; but it will be understood from Fig. 2 that the rheostat is first inserted into casing 53, after which the switch base 25 with its assembled parts is inserted, whereupon the aforementioned lugs 55, 55 and 56 are bent inwardly to retain the rheostat and switch in assembled relation as a unit. The threaded bushing 57 in Fig. 2 is adapted to provide for the well-known form of one-hole mounting, in conjunction with a clamping nut or nuts (not shown).
- 50 As best illustrated in Fig. 3, in dotted lines at 35, 36 and 37, the provision of diaphragms for those sub-recesses not required in the construction of a given switch mechanism insures substantial dust-tightness of the switch chamber when the switch is mounted in the manner shown. The parts 58, 59 and 60 in Fig. 3 are the wiring terminal elements of the radio rheostat or volume control potentiometer with which my switch mechanism may be employed. All of the switches herein disclosed have the following alternative ratings: 10 amperes at 12 volts; 3 amperes at 125 volts, and 1 ampere at 250 volts.
- 65 In constructing the double pole single throw switch of Figs. 7 and 8, all of the aforescribed parts are employed, and the same are arranged in an identical manner, as indicated by the like numerals of reference applied thereto. In addition, however, the diaphragms are broached out from the sub-recesses 35, 36 and 37, to respectively accommodate the wiring terminal portion 48^a of a one-piece resilient contact 48 and the securing rivet 43^a therefor, and to accommodate a second combined contact and wiring terminal member 41. The member 48 may be formed from a blank identical with that employed for member 42 aforescribed, but is merely bent in an opposite manner, whereby both right-hand and left-hand resilient contact and terminal members are provided. Considering Figs. 7 and 14, it is to be understood that for this double pole switch two of the contactors 47 are employed, one of the same being positioned in plate opening 28^c (as in Fig. 1) and the other being positioned in plate opening 28^b (as indicated in dotted lines in Fig. 7). The contact arm of member 48 is designated by the reference character 40^c, the same having a contact tip 40^d.
- 15 In Figs. 7 and 8 plate 28 is shown in its extreme counter-clockwise position to effect interruption of both branches or lines of the circuit to be controlled thereby; whereas upon movement of the plate to its extreme clockwise position both lines of the controlled circuit will be completed. 20 Where an electrical function the reverse of that provided by the arrangement of Figs. 7 and 8 is desired, the same may be obtained by merely transposing the contactors 47 from plate openings 28^b and 28^c to plate openings 28^c and 28^b, 25 respectively. With such an arrangement of the contactors both lines of the controlled circuit would be completed in the extreme counterclockwise position of plate 28, and such circuit would be interrupted in the extreme clockwise position 30 of said plate. Various modifications of the aforescribed arrangement will at once suggest themselves to those skilled in the art. Thus, by merely properly attaching the circuit wires (not shown) the switch of Figs. 7 and 8 may be utilized to simultaneously complete and interrupt two separate circuits. Or, with reference to Figs. 7 and 8, if the contactor 47 be moved from plate opening 28^b to plate opening 28^c one of the two circuits will be completed simultaneously with 40 interruption of the other circuit, and vice versa. A reversal of the electrical functions last described may be obtained by permitting the contactor 47 to remain in plate opening 28^b and transposing the other contactor 47 from plate 45 opening 28^c to plate opening 28^b.
- 35 In Figs. 9 and 10 I have shown a three-way switch without "off" position. Although it is possible to employ a base like that designated by the numeral 25 in the switches heretofore described, 50 I prefer to employ a base 61 which differs from base 25 only in respect of having in its lower surface a groove 62 which accommodates bus member 63 over the perforated ends of which the rivet shanks 43^a are upset to provide a permanent 55 electrical connection between the pair of resilient stationary contact members designated by numerals 42^c and 43^c. Inasmuch as only one wiring terminal portion is required for the contact members 42^c and 43^c, the integral wiring terminal portion 48^a has been retained in the device of Figs. 9 and 10, whereas the portion 42^a (Fig. 9) has been cut off or shortened to prevent exposure thereof below the lower surface of base 61.
- 60 As shown in Fig. 10 two contactors 47 are respectively positioned within the openings 28^c and 28^b in plate 28. Thus in the extreme counter-clockwise position of plate 28 a circuit will be completed from terminal 48^a through its integral contact portion 48^c, contact tip 48^d, through the 65 right-hand contactor 47 (Fig. 10), to and through the right-hand combined contact and terminal member 41. Upon extreme clockwise positioning of plate 28, an alternative circuit will be completed from wiring terminal portion 48^a 70
- 70
- 75

through bus member 63 to resilient contact portion 42^c and tip 42^d through the left-hand contactor 47, to and through the left-hand combined contact and terminal member 41. A three-way 5 switch having characteristics the reverse of those just described may be provided by simply transposing the two contactors 47 from plate openings 28^c and 28^d to plate openings 28^e and 28^f, respectively. 10 The so-called four-wire switch shown in Figs. 11 and 12 is substantially like the double pole single throw switch of Figs. 7 and 8, and like parts have been given like numerals of reference. In the switch of Figs. 11 and 12, however, I provide a bus member 64 having end perforations to 15 accommodate the shank portions of the pair of contactors 47. Bus member 64 is thus positioned between the lower surface of plate 28 and the heads 47^a of the contactors, to provide a continuous electrical connection between the latter. 20 The switch is shown in "off" position in Figs. 11 and 12, but upon extreme clockwise positioning of plate 28 the contactors 47 are engaged with their respectively cooperating pairs of stationary 25 contacts; and inasmuch as contactors 47 are electrically connected with each other, it follows that all of the four wiring terminals are electrically connected with each other in the "on" 30 position of the switch. Such a switch may be employed for control of the "A", "B" and "C" battery supply in a radio receiving set.

Although the bus member 64 in Figs. 11 and 12 is shown as comprising a straight strip which underlies the opening 28^c in plate 28, it will be 35 apparent from Fig. 11 that the intermediate portion of said bus member might be offset toward the plate opening 28^c to afford clearance for a third contactor to be inserted within said plate opening 28^c. With an arrangement like 40 that just described, and with the other switch parts in the positions thereof shown in Figs. 11 and 12, a circuit would be completed between terminal 48^a and the right-hand terminal 48 (Fig. 12) independently of the other switch terminals. Various other modifications and 45 arrangements of the switch parts will be apparent to those skilled in the art as the occasions therefor arise.

In Fig. 13 I have shown a resilient stationary 50 contact and terminal member 65 which is formed from a bi-metallic punching. The lower layer 65^a of this element preferably consists of coin silver, and the upper layer 65^b thereof may consist of phosphor bronze, beryllium copper, or even ordinary pure copper. A member so constructed has the necessary resiliency, is extremely long-lived, and has a relatively high current controlling 55 capacity.

The aforementioned plate 28 shown in Fig. 14 60 is preferably punched from a laminated sheet of fibrous material impregnated with a phenol formaldehyde condensation product.

In the fragmentary view of Fig. 15 I have 65 shown a one-piece combined contact and terminal member 66 which is insertable downwardly through an opening (such as 27) provided in the bottom wall of base recess 26, said member having shoulders 66^a, 66^b formed at the upper end thereof for engagement with the bottom wall of 70 recess 26. The upper or contact edge 66^c between said shoulder portions is preferably arranged flush with the bottom wall of said recess 26, for cooperation with a contactor 47 of the character aforescribed. Member 66 is provided with lugs 66^d and 66^e (shown in dotted 75

lines) which are bent to the full line positions thereof against the lower surface of base 25 to rigidly and permanently secure said member to said base.

The single pole single throw switch illustrated 5 in Figs. 16 to 20 may be substantially like that shown in Figs. 1 to 6, and like parts have been given like numerals of reference. In this modified device, however, a special form of actuating 10 element is provided, and the switch base is mounted in a novel manner to provide for operation thereof by means located laterally of the switch. If it be assumed that the aforescribed base 25 is employed, the peripheral wall of the latter is ground out or otherwise removed to provide an upwardly opening notch the side walls of which are designated by the numerals 67 and 68 in Fig. 16; or a base 25 having such a notch formed therein by the molding operation may be 15 employed. Said notch provides clearance for the laterally extending forked end 69^a of an actuating member 69, which is punched and stamped from sheet metal. Member 69 is provided with a bearing opening 69^b to accommodate the portion 30^c of the pivot post, as shown in dotted 20 lines in Fig. 16. The inner end 69^d of member 69 is bent downwardly to lie within the plane of plate 28, as heretofore described in connection 25 with the other forms of switches; and said end is provided with an opening 69^e to accommodate 30 the diametrically extending end portion of spring 48.

As shown in Figs. 16 to 19, base 25 is seated 35 within a stamped sheet metal member 70 having an inturned flange 70^a which engages the lower surface of base 25, three lugs 70^b, 70^c and 70^d extending inwardly from said flange and the same being bent into the corresponding recesses provided in the lower surface of base 25, as illustrated at 70^e in Fig. 19, to restrain said parts 40 against relative rotation. Member 70 is preferably provided at its upper end with three lugs 70^f, 70^g and 70^h which are respectively engaged with correspondingly shaped notches in a metal 45 plate 71 (Fig. 17), said lugs being bent inwardly over plate 71 to rigidly secure said parts to each other. Plate 71 is provided with an opening 71^a of approximately circular form, the wall of which is provided with notches. Opening 71^a is adapted 50 to accommodate the reduced end 72^a of a hollow metal bushing 72, said reduced end being upset over that surface of plate 71 against which switch base 25 abuts, as best illustrated in Fig. 19, to insure against rotary displacement of plate 71 55 with respect to said bushing.

Plate 71 is provided at its upper end (Fig. 19) with an inwardly extending lug 71^b which acts as a stop for engagement by a lug 73^a formed on a disk 73 to limit the degree of oscillatory movement of the latter in each direction. Disk 73 is rigidly and non-rotatably secured to a shaft 74 by an upsetting operation, as shown at 74^a in Fig. 19. Disk 73 is provided with a lug 73^b extending inwardly therefrom into the plane of the main body portion of member 69, whereby lug 73^b is transiently engageable alternately with the respective extensions 69^a of member 69 upon rotation of shaft 74 in opposite directions. Thus, with reference to Fig. 18, wherein the switch is shown in "off" position, it will be apparent that upon a given degree of counterclockwise rotation of shaft 74 the switch will be thrown to "on" position, and the shaft may be rotated farther in a counterclockwise direction pending engagement 75

of lug 73^a with the right-hand side of lug 71^b. In practice the shaft 74 is connected at its inner end, either directly or by means of a flexible member attached thereto, with the contact element of a radio rheostat or the like which is located at a point remote from the switch 25.

Thus it may be assumed that the part 75, Figs. 18 and 19, designates an automobile dashboard. Dashboard 75 is provided with an opening 75^a to accommodate the reduced and threaded end 72^b of bushing 72, said bushing being rigidly clamped to dashboard 75 as by means of a nut 76. Shaft 74 is preferably provided with a peripheral groove 74^b which accommodates a washer 77 of horse-shoe shape, whereby inward displacement of the shaft with respect to the bushing is prevented. Fitted over the outer end of shaft 74 is a knob 78, preferably consisting of molded insulation, said knob having a threaded lateral opening 79 formed therein to accommodate a set screw 80, which when tightened is adapted to restrain the knob against rotation relatively to the shaft.

What I claim as new and desire to secure by Letters Patent is:

1. In an electric snap switch, in combination, a recessed molded insulating base, a flat plate of insulating material pivotally supported upon the bottom wall of said base for movement in parallel spaced relation thereto from one extreme position to the other, said base and said plate having cooperating parts formed integrally therewith to limit such movement, the free end of said plate being relatively wider than the main body portion thereof and said end being provided with four openings arranged in an arc concentric to the pivot point, a pair of contactors of like form having enlarged hemispherical heads and cylindrical shank portions, the shank portions of said contactors being freely inserted upwardly and slidably positioned within two of said openings on opposite sides respectively of the center line of said plate, said contactors being restrained by the walls of said openings against substantial movement transversely of said plate, a plurality of pairs of aligned stationary contacts respectively positioned above and below said plate, the contacts of said pairs being adapted for simultaneous or alternate engagement by the respective contactors, according to the positioning of the latter within the openings, and means additional to said contactors to provide a common electrical connection for all of said contacts in one extreme position of said plate upon positioning of said contactors with one of said plate openings therebetween, said last mentioned means including a separately formed bus member carried by and electrically connecting said contactors.

2. In an electric switch of the snap make and break type for radio rheostats and the like, in combination, a molded insulating base having a recess opening to the upper surface thereof, said recess having a relatively small substantially rectangular opening formed in the bottom wall thereof, a one-piece, flat, punched sheet metal contact and terminal member positioned edge-wise within said opening, said metal member having shoulders formed thereon for respectively engaging the bottom wall of said recess and the bottom surface of said base, certain of said shoulders being formed by an edge-wise upsetting operation after insertion of said member into said opening, said metal member having a punched upper edge forming a contact portion

located in a plane substantially flush with the bottom wall of said recess, an insulating plate positioned within said recess in parallel relation to the bottom wall thereof and movable transversely with respect thereto, a contactor loosely carried by said insulating plate and slidably movable thereby in said plane into and out of engagement with said contact portion, said contactor being restrained by said plate against substantial transverse movement relatively thereto, said metal member having a perforated end portion projecting downwardly from the lower surface of said base to provide for attachment of a terminal wire, and a second one-piece combined contact and wiring terminal member having a resilient contact portion positioned above and biased toward said contact portion first mentioned.

3. In an electric switch of the snap make and break type for radio rheostats and the like, in combination, an insulating base having a relatively small substantially rectangular opening formed therein, a one-piece, flat, punched sheet metal contact and terminal member positioned edge-wise within said opening, said metal member having shoulders formed thereon for respectively engaging the upper and lower surfaces of said base, the shoulders engaging the upper surface of said base being upset edge-wise after insertion of said metal member into said opening whereby said metal member is rigidly and permanently attached to said base, said metal member having a punched upper edge forming a contact portion located in a plane substantially flush with the upper surface of said base, a punched insulating plate movable transversely with respect to said base, a contactor loosely carried by said insulating plate and slidably movable thereby in said plane into and out of engagement with said contact portion, said contactor being restrained by said plate against substantial transverse movement relatively thereto, said metal member having an integral portion projecting downwardly from the lower surface of said base, said last mentioned portion having an opening formed therein to facilitate attachment of a terminal wire, and a second one-piece combined contact and wiring terminal member having a resilient contact portion positioned above and biased toward said contact portion first mentioned.

4. In an electric snap switch, in combination, an insulating base having a relatively small substantially rectangular opening formed therein, a one-piece, flat, punched sheet metal member positioned edge-wise within said opening, said member having shoulders formed thereon within the plane thereof for respectively engaging the upper and lower surfaces of said base, certain of said shoulders being upset edge-wise after insertion of said member into said opening whereby said member is rigidly and permanently attached to said base, said member having a punched upper edge forming a contact portion located in a plane substantially flush with the upper surface of said base, said member having an integral portion projecting downwardly from the lower surface of said base, said last mentioned portion having an opening formed therein to facilitate attachment of a terminal wire, a second one-piece combined contact and wiring terminal member having a contact portion positioned above and resiliently biased toward said contact edge portion aforementioned, a flat punched plate of insulating material continu-

ously interposed between said contact portion and said contact edge portion, said plate having an opening formed therein, and a hemispherical headed contactor the head portion of which is 5 interposed between said plate and said base and the substantially cylindrical shank portion of which is loosely positioned within said plate opening, to provide for sliding movement of said contactor into and out of bridging engagement 10 with said contact portions.

5. A combined radio rheostat and switch comprising, in combination, a one-piece inverted cup-shaped metal casing, said casing having a centrally located circular opening in the upper end 15 wall thereof, a rheostat base and a switch base consisting of a pair of molded insulating members of cylindrical form and of substantially identical peripheral dimensions, both inserted upwardly in sequence into said one-piece casing 20 and interlocked with the latter against rotation with respect thereto, an operating shaft carried by said rheostat base and projecting beyond said casing through said opening in the upper end wall of the latter, a snap switch mechanism 25 carried by said switch base and having an operative connection with said operating shaft, said casing having a plurality of spaced lugs formed integrally therewith and bent inwardly over the lower surface of said switch base to retain said 30 parts in assembled relation, said snap switch mechanism including a plurality of one-piece combined contact and wiring terminal members the wiring terminal portions of which penetrate said switch base and are exposed at the lower 35 surface of the latter, and said lugs being so arranged as to provide ample electrical clearance between the same and said wiring terminal members.

6. In a snap switch mechanism of the character described, in combination, an insulating base, a flat insulating plate pivotally supported for oscillatory movement in a plane parallel to said base, said plate having an opening formed 40 therein adjacent to the free end thereof, a bridging contactor having a cylindrical shank portion freely insertable upwardly through and loosely positioned within said plate opening, the upper end of said shank portion being substantially hemispherical and the same extending a 45 substantial distance above the upper surface of said plate, said contactor having a substantially hemispherical head portion interposed between said plate and said base, a pair of aligned sheet metal contacts secured to said base and respectively positioned above and below said plate, the 50 lower contact having an edge portion thereof located in a plane substantially flush with the surface of said base for engagement by said contactor head, the upper contact being resilient and the same being formed to facilitate sliding engagement thereof by the shank end of said contactor, a pivotally supported sheet metal actuating member, and a spring interposed between said actuating member and said plate.

65 7. In an electric snap switch for radio rheostats and the like, in combination, an insulating base, said base having a relatively small substantially rectangular opening formed therein, a rigid one-piece, flat punched sheet metal contact 65 and terminal member positioned edgewise within said opening, said member having shoulders formed at one end thereof and engaged with one surface of said base, said end being adapted to provide a contact surface, said member also having a pair of lugs formed integrally therewith 70

and bent edgewise into engagement with the other surface of said base, whereby said member is rigidly and permanently attached to said base, said member having an integral end portion projecting downwardly from the lower surface 5 of said base, said end portion having an opening formed therein to provide for attachment of a terminal wire thereto, a second one-piece, combined contact and wiring terminal member rigidly attached to said base and having a contact 10 portion spaced from said contact surface first mentioned, an insulating member movable transversely of said base in a plane parallel to the latter, a contactor loosely carried by said insulating member and bodily movable thereby 15 transversely of said base in opposite directions respectively into and out of bridging engagement with said contact surface and said contact portion, said contactor being restrained by said insulating member against substantial transverse movement relatively to the latter, and means including a coiled, over-the-center spring for effecting such movements of said insulating member and said contactor with a snap action.

8. In an electric snap switch for radio rheostats and the like, in combination, an insulating base, said base having a relatively small substantially rectangular opening formed therein, a one-piece combined contact and wiring terminal member consisting of a flat, substantially rigid sheet metal punching, the terminal shank of said member being insertable downwardly into said opening and the contact head thereof having shoulders to limit said downward movement and to provide a contact surface exposed at the upper surface of said base, said terminal shank having integral lugs bent edge-wise over the lower surface of said base to rigidly and permanently secure said member in position, a second one-piece, combined contact and 40 wiring terminal member rigidly attached to said base and having a contact portion spaced from said contact surface first mentioned, an insulating member movable transversely of said base in a plane parallel to the latter, a contactor 45 loosely carried by said insulating member and bodily movable thereby transversely of said base in opposite directions respectively into and out of bridging engagement with said contact surface and said contact portion, said contactor being restrained by said insulating member against substantial transverse movement relatively to the latter, a punched and stamped sheet metal actuating element pivotally secured on said base, means including a coiled, over-the-center 50 spring interposed between said actuating element and said insulating member for effecting snap movements of the latter from each extreme position thereof to the other, and an operating member having a lost-motion driving connection 55 with said actuating element.

9. In a snap switch mechanism of the character described, in combination, an insulating base, a flat insulating plate pivotally supported 65 for oscillatory movement in a plane parallel to said base, said plate having an opening formed therein adjacent to the free end thereof, a bridging contactor having a cylindrical shank portion freely insertable upwardly through and loosely positioned within said plate opening, the upper 70 end of said shank portion being substantially hemispherical and the same extending a substantial distance above the upper surface of said plate, said contactor having a substantially hemispherical head portion interposed between 75

said plate and said base, a pair of alined metal contacts secured to said base and respectively positioned above and below said plate, the lower contact having a portion thereof located in a plane substantially flush with the surface of said base for engagement by said contactor head, the upper contact being resilient and the same being

formed to facilitate sliding engagement thereof by the shank end of said contactor, a pivotally supported sheet metal actuating member, and a spring interposed between said actuating member and said plate.

GEORGE J. MEUER.
